UNITED STATES PATENT OFFICE.

OSCAR R. RYDQUIST, OF ST. CROIX FALLS, WISCONSIN.

OIL-CAN.

1,138,794.

Specification of Letters Patent.

Patented May 11, 1915.

Application filed June 3, 1914. Serial No. 842,599.

To all whom it may concern:

Be it known that I, OSCAR R. RYDQUIST, a citizen of the United States, residing at St. Croix Falls, in the county of Polk and State 5 of Wisconsin, have invented certain new and useful Improvements in Oil-Cans; and I do hereby declare the following to be a full, clear, and exact description of the invention, such as will enable others skilled in the art 10 to which it appertains to make and use the same.

My invention relates to oil cans of the class wherein the operator forces oil through the spout by pressure, as will be apparent 15 from the following specification, reference being had to the accompanying drawings which are made a part of this application in which,

Figure 1 is a central longitudinal section, 20 Fig. 2 is an end view, Fig. 3 is a plan view of the piston.

In the detailed description of my invention numerals will be used to designate the various parts, the same numeral being used 25 for the same part throughout.

My invention consists of an oil can of which the body portion 1, is practically divided into two chambers 2 and 3 by a piston 4 the relative size of the chambers being 30 governed by the position of the piston therein. Said piston is connected by a piston-stem 5 to a hand grip 6. A valve 7 is hingedly mounted on said piston to permit the oil to flow from chamber 2 to chamber 3. 35 The piston is made wedge shaped, its upper edge being a little thicker than the diameter of the opening to the spout, to furnish a closure for said opening to prevent the siphoning of the oil from the can when held 40 suspended in the hand. The wedge shape is preferred, to save weight and material in the construction thereof. A spiral spring 8 is mounted on the piston stem to hold the piston in and return it to its inwardly normal 45 position when not controlled by pressure of the fingers on the hand grip 6.

A tapered spout 9 is connected by screw threads to the top side of the can and it extends along said side parallel thereto and 50 beyond the front end thereof. Legs or supporting members 10 are fastened to the bottom side of the can to prevent its rolling when lying on its side. A handle 11 is vertically positioned on the rear end of the can, 55 extending back from the end of the can a sufficient distance to permit the hand-grip 6

to be moved rearwardly the full length of the piston stem 5. At one side of the handle a guiding groove 12 is formed by pressing inwardly the edges of said handle and one 60 end 13 of the hand-grip is slidably mounted in said guiding groove to prevent the hand grip from rotating thus maintaining it in its operative position.

For the purpose of filling the can an 65 opening 14, having a threaded closure 15, is provided at the forward end of the can, said closure having an extension 16 through which an aperture 17 is formed to furnish a means for hanging up the oil can if desired. 70 A spring controlled valve 18 is provided on the upper side of the front end of the oil can to permit air to enter therein.

On the inside of the can a plurality of stops 19 are placed to control the distance 75 which the piston may be moved. Where the piston stem passes through the end of the can a stuffing box 20, having a threaded cap 21, is provided to prevent the leaking of oil.

In operating the oil can, the chamber 2 is 80 filled with oil through the opening 14. The oil flows through the valve 7 into chamber 3.

When in use the can is held horizontally 85 in the hand by grasping the handle and the hand grip 6. When it is desired to force the oil out, a slight tightening of the grip of the hand will pull the piston-stem out and cause a pressure to be exerted on the oil in chamber 3 by the piston and thus force it 90 out of the spout at the will of the operator.

The peculiar arrangement of parts in the location of the handle and spout, and the spout being attached by screw threads, permitting it to be turned at an angle with 95 the body portion if desired, will enable the operator to oil bearings located in places practically inaccessible to an ordinary form of oil can.

Having thus fully described my invention in the foregoing specifications and illustrated in the accompanying drawings the preferred construction and combination of parts deemed necessary in materializing my invention, I wish it understood that I 100 wish to comprehend in this application all substantial equivalents and substitutes which may be considered as falling fairly within the scope of my invention.

What I claim and wish to secure by Letters Patent is:

1. An oil can comprising an oblong cy-

lindrical body portion of uniform diameter throughout its length, a spout removably secured to said body portion adjacent one end thereof and normally disposed parallel 5 with the body, a piston of a diameter equal to the diameter of the body portion, said piston being greater in width at one edge than at the other, a stem attached to the piston and extended through one end of the 10 body portion, a hand-grip attached to said stem, a spring surrounding said stem whereby the piston is held normally inward, a valve pivotally secured to the piston, a guide for said hand-grip, an air vent for 15 said body portion, and a plurality of stops adapted to limit the movement of the piston in the body portion.

2. The combination with an oil can; of a wedge shaped piston, having a suitable 20 valve operatively mounted therein and connected by a stem to a hand-grip; a plurality

of stops fixedly placed upon the inside of the body portion; a spiral spring surrounding the piston-stem; a handle mounted on the end of the can; a guiding groove within 25 the said handle; a hand-grip attached to the piston stem and having one end of said hand-grip slidably mounted in said groove; a spout operatively fastened to and normally extending parallel with the top side 30 of said can; supports on the lower side of said can whereby it is kept in proper position when not in use, and an air vent on the upper side of the front end of said oil can. 35

In testimony whereof I have signed my name to this specification in the presence of two subscribing witnesses.

OSCAR R. RYDQUIST.
